(57) **CLAIM**

The ornamental design for a space heater as shown and described.

DESCRIPTION

FIG. 1 is a front, right and top perspective view of a space heater, showing my new design.

FIG. 2 is a rear, left and bottom perspective view thereof, shown in a first configuration of use.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is another rear, left and bottom perspective view of the space heater shown in FIG. 1, shown in a second configuration of use; and,

FIG. 10 is another rear, left and bottom perspective view of the space heater shown in FIG. 1, shown in a third configuration of use.

The dashed broken lines depict portions of the space heater that form no part of the claimed design.

1 Claim, 10 Drawing Sheets
